DESIGN FOR A CLOCK-CASE

Frederic Remington Borgfeldt, Wilmette, Ill., assignor to Middlebury Electric Clock Corporation, Chicago, Ill., a corporation of Illinois

Application February 14, 1934, Serial No. 50,717

Term of patent 3½ years

To all whom it may concern:

Be it known that I, Frederic Remington Borgfeldt, a citizen of the United States, residing at Wilmette, in the county of Cook and State of Illinois, have invented a new, original, and ornamental Design for Clock-Cases, of which the following is a specification, reference being had to the accompanying drawing, forming part hereof, wherein

Fig. 1 is a front elevation of a clock-case showing my new design, and

Fig. 2 is a side elevation of the clock-case of Fig. 1.

I claim:

The ornamental design for a clock-case as shown.

FREDERIC REMINGTON BORGFELDT.
